[57] CLAIM

The ornamental design for a conductor terminal junction module, as shown and described.

DESCRIPTION

FIG. 1 is a top plan view of the conductor terminal junction module showing my new design;

FIG. 2 is a bottom plan view thereof;

FIG. 3 is a left side elevational view, the right side being a mirror image thereof;

FIG. 4 is a rear elevational view thereof;

FIG. 5 is a front elevational view thereof, and

FIG. 6 is a front perspective view thereof.
